PORTABLE SPRAYER

Harold D. Johnson, Emmetsburg, Iowa, assignor to Aero-Dyne Corporation, Emmetsburg, Iowa, a corporation of Iowa

Filed Jan. 11, 1962, Ser. No. 68,260

Term of patent 14 years

(Cl. D62—2)

FIGURE 1 is a side elevational view of a portable sprayer embodying my new design.

FIG. 2 is a top plan view thereof.

FIG. 3 is a front elevational view thereof.

FIG. 4 is a fragmentary rear elevational view thereof. The characteristic features of my new design reside particularly in the spray gun portion thereof as shown.

I claim:

The ornamental design for a portable sprayer, as shown and described.
